GEORGE SEARS NEVES AND ARNALDO DOS SANTOS VIGAS, OF SOMERVILLE,
MASSACHUSETTS

WATERPROOF POCKET

Application filed June 1, 1929. Serial No. 367,768.

The object of this invention is to provide a device constituting a receptacle which will effectively prevent the contents thereof from getting moist or wet, under any conditions such as those encountered by persons bathing, or exposed to severe weather.

A further object is to provide a device which shall include the inner and outer portions of a pocket, means for clamping these portions, means for retaining the pocket on a belt or the like, and a plurality of oppositely located strips within the upper portions of the walls of the pocket, adapted to engage each other under the influence of the clamping means.

With the foregoing and other objects in view, the invention consists in the novel construction and arrangement of elements disclosed, it being understood that modifications may be made within the scope of the claims without departing from the spirit of the invention.

In the drawings forming part of this application:—

Figure 1 is a view of the pocket in elevation, with the clamping device applied thereto.

Figure 2 is also in elevation, from the opposite side.

Figure 3 is a plan view, showing the upper edge portions of the elements.

Figure 4 is an elevation showing a side edge.

Figure 5 is a section on an enlarged scale and in a plane represented by line 5—5 of Figure 2.

Figure 6 is a detail on an enlarged scale, showing the elements of the clamp as they appear looking from the right in Figure 3.

The outer walls of the pocket are designated 10 and 11, and inner walls or lining elements are shown at 10' and 11'.

Along the upper edges of the walls, and facing each other are strips 13 and 14 of cork or other suitable material, these strips providing the elements designed to effect water tight connection. Sponge rubber is especially satisfactory for this purpose.

In order to effect positive connection, clamping elements are employed, including

bars or strips 16 and 17, element 16 having eyes at the end portions as shown at 18, and retaining devices of T construction being pivoted within these eye portions. Said elements are designated 19 and are threaded as shown at 19', being engaged by caps or cap nuts 20. The devices 19 are adapted to swing around the outer edges of the pocket as shown and the function thereof is apparent. Loops or other devices 21, 22 and 23 are provided for the clamping bars or strips and other loops 24 and 25 are provided for securing the pocket by means of a belt or the like.

What is claimed is:—

A waterproof pocket comprising front and rear walls, each consisting of an outer ply and a lining ply, the latter of waterproof material the outer plies extending above the upper edges of the inner plies at the mouth of the pocket, strips of yieldable, water-proof material upon the inner side of each ply of said walls at the mouth of the pocket in facial contact with each other, metal strips mounted upon the outer sides of said walls above the upper edges of the inner plies, one of said strips being provided in each end with a notch, the other strip being provided with spaced pintle lugs at its ends, T-bolts having their head ends engaged in said lugs whereby the said bolts may be swung to position with their shanks extending across the side edges of the walls and with their free ends engaging in the notches of the other strip, and nuts threaded onto the said ends of the shanks and bearing against the notched ends of said other strip, the yieldable, first mentioned strips constituting means for holding the walls of the pockets in spaced relation to each other.

In testimony whereof we affix our signatures.

GEORGE SEARS NEVES.
ARNALDO DOS SANTOS VIGAS.
